UNITED STATES PATENT OFFICE.

CALEB D. BRADHAM, OF NEWBERN, NORTH CAROLINA.

SHIPPING-TAG.

No. 812,633.

Specification of Letters Patent.

Patented Feb. 13, 1906.

Application filed June 29, 1905. Serial No. 267,601.

To all whom it may concern:

Be it known that I, CALEB D. BRADHAM, a citizen of the United States, residing at Newbern, in the county of Craven and State of North Carolina, have invented a new and useful Shipping-Tag, of which the following is a specification.

This invention relates to shipping-tags. The object of the invention is to provide a novel form of combined holder and tag in the use of which a tag may be positively positioned relatively to the holder and be detached when desired, and, further, to cause the holder to constitute a return-tag should the tag proper be lost.

With the above and other objects in view, as will appear as the nature of the invention is better understood, the same consists in the novel construction and combination of parts of a shipping-tag, as will be hereinafter fully described and claimed.

In the accompanying drawings, forming a part of this specification, and in which like characters of reference indicate corresponding parts, Figure 1 is a plan view exhibiting a portion of a box or crate displaying the combined holder and tag of the present invention secured thereto. Fig. 2 is a longitudinal sectional view taken on the line 2 2, Fig. 1. Fig. 3 is a perspective detail view of the tag, exhibiting the return side of the same. Fig. 4 is a perspective view of the holder, exhibiting the manner in which the owner's name is displayed to insure return of the crate should the tag become detached from the holder.

The holder comprises a plate 1, which may be made of any suitable material, preferably of tin or zinc, and has three of its sides inturned upon themselves to form combined guides and tag-holders 2, 3, and 4 and the remaining side or end being projected, preferably on inward-converging curved lines, beyond the body portion, forming an extension 5, that is provided with an orifice 6 to receive a holding-screw 7, the two corners of the body opposite the extension 5 being provided with orifices 8 to receive holding-screws 9. The object of the extension 5 is to facilitate the positioning and removing of the tag 10, which may be made of any suitable material, preferably of paper, and has one end provided with a rounded extension 11, the crest of which is formed with a semicircular notch 12 to engage with the head of the screw 7. It will be seen that as the extension 11 projects some distance beyond the guides 2 4 it may readily be

lifted out of engagement with the screw when the tag is to be positioned or reversed without interfering with the screw, the notch 12 being designed to engage with the under side 60 of the screw-head, as clearly shown in Fig. 2. It will be noted by reference to Fig. 1 that the extension 11 terminates some distance short of the periphery of the extension 5, the object of this arrangement being to protect 65 the extension 11 against being lifted or torn when the receptacle to which the tag is attached is handled. The tag will have on its obverse side the name of the consignee and a serial number to identify the package and 70 also a notice to the effect that on its reverse side is the return address of the consignor, this being shown in Fig. 3. The coaction between the tag and the guides 2 4 and screw 7 will always cause the tag to be positively held 75 in the holder; but should the tag become detached from any cause there is provision made whereby the name of the consignor of the package will be displayed, and this is accomplished by stamping the name in the 80 body of the holder, as shown in Fig. 4. The stamping may be done from the front of the holder or from the back, as preferred; but the former will be preferred, inasmuch as it will obviate the presentation of protuberances that will prevent the tag from having a flat and unbroken surface against which to bear, which would detract from the stability of its connection with the holder.

The extension on the holder and on the tag 90 are of peculiar value and advantage, inasmuch as the positioning of the tag is greatly facilitated thereby, and, further, the detaching of the tag from the holder for the purpose of reversal may readily and easily be accomplished. The semicircular notch 12 is also of importance, as it obviates the necessity of punching the tag to receive the screw 7, and, further, it will facilitate the disconnection of the extension 11 from engagement with the 95 screw-head.

Having thus described the invention, what is claimed is—

1. A shipping-tag embodying a holder having marginal guides and an extension at one end provided with an orifice, and a tag adapted to engage the guides and provided at one end with an extension terminating in a notch in alignment with the orifice.

2. The combination with a receptacle of a holder provided with marginal guides and having at one end an extension provided with

an orifice, an attaching device engaging the orifice, and a tag adapted to engage the guides and having one end provided with an extension having a notch to engage the attaching device.

3. The combination with a receptacle, of a holder having the name of the sender stamped thereon and provided with marginal guides and with a terminal extension having an orifice, an attaching device engaging the orifice, and a tag adapted to engage the guides and

provided at one end with a reduced extension having a notch to engage the attaching device.

In testimony that I claim the foregoing as my own I have hereto affixed my signature in the presence of two witnesses.

CALEB D. BRADHAM.
